UNITED STATES PATENT OFFICE.

ELIAS S. ELLIOTT, OF RICH SQUARE, NORTH CAROLINA.

BEDSTEAD-BRACE.

SPECIFICATION forming part of Letters Patent No. 469,081, dated February 16, 1892.

Application filed October 15, 1891. Serial No. 408,785. (No model.)

To all whom it may concern:

Be it known that I, ELIAS S. ELLIOTT, a citizen of the United States, residing at Rich Square, in the county of Northampton and State of North Carolina, have invented new and useful Improvements in Clamping Devices for Bedsteads, Tables, Desks, &c., of which the following is a specification.

This invention relates to an improved clamping device for holding the sides of bedsteads and other articles of furniture having rectangular frames in parallel positions.

The invention also relates to the combination, with a bed-brace, of a frame adapted to fit thereon and support the central part of the bed spring or slats, as hereinafter described.

The accompanying drawing is a perspective view of my invention complete with dotted outlines of a bed-frame.

The invention consists in the combination and arrangement, as hereinafter described, of a set of four metallic plates A A' A'' A''', which are secured to the under surfaces of the sides of the bed-frame or other article of furniture to be braced by means of wood-screws b b' b'' b'''. Each plate is provided with a perforated inner end, parallel sides, and beveled outer end, the latter provided

30 with a turned-up flange, as shown at c c' c'' c'''.

As above indicated, four plates constitute a set, two of which have their flanged edges inclined to the right and two to the left, so that the duplicate plates may be secured diagonally opposite one another and their connecting-braces E F be made to cross each other, as shown.

Each brace is composed of two rods g h, having hooked outer ends to engage the plates A A' A'' A''' and inner ends provided with 40 heads and screws, respectively, as shown. Swivel-frames I are fitted on the said inner ends of the rods to permit of their being drawn toward one another or be otherwise adjusted.

The peculiarity of my brace is that the rods 45 cross one another and connect with angle-plates that are applied to the sides of the furniture-frame, thus insuring rigidity to the whole structure without injury to any part thereof.

The letter L designates a sled-shaped frame composed of side pieces m m' and connecting-rods n n'. The lower edges of the side pieces are notched, as at o o', so as to rest securely 55 on the braces, as shown, and thus form a central support for a bed spring or slats.

Having described my invention, what I claim as new, and desire to secure by Letters Patent, is—

In combination with a bed-frame, a pair 60 of diagonally-arranged sectional braces, connecting swivel-frames, and beveled fastening-plates, as described, with a detachable sled-shaped frame, the side pieces of the latter notched, substantially as and for the purpose 65 set forth.

In testimony whereof I affix my signature in presence of two witnesses.

ELIAS S. ELLIOTT.
